ART OF TREATING SKINS

Matthew M. Merritt, Middleton, Mass., assignor
to The Tanning Process Company, Boston,
Mass., a corporation of Massachusetts

Application March 10, 1936, Serial No. 68,090

5 Claims. (Cl. 149—6)

This invention relates to treatment of skins following tanning operations. While the invention will be described with reference to the putting-out of skins and the securing of them to drying boards following tanning and/or coloring operations, it will be understood that the invention and various characteristics thereof may have other applications and uses.

It is an object of this invention to expedite the processing of skins following tanning and/or dyeing operations. It is a further object of the invention to provide a simple, inexpensive, and especially efficient apparatus for practising a method by which certain operations on skins may be facilitated.

To these ends and in accordance with an important characteristic of the invention a skin is slicked out upon a drying board while still wet with tanning or dyeing solutions and substantially simultaneously therewith is secured to the board around the margin of the skin progressively with the slicking-out operation on successive portions of the skin until all portions of the latter have been slicked out and secured to the drying board. Conveniently the skin and its supporting board are shifted continuously in one direction about an axis normal to the board so that as the marginal portions of the skin pass by a given station both putting-out and fastening inserting operations are performed upon successive portions of the skin with the result that at the end of the travel of the skin all portions thereof have been put out and secured in place on the drying board.

For practising the method, there is provided an improved apparatus comprising a rotary work support arranged at a substantial angle to the horizontal, together with means under the control of an operator to rotate the work support so that successive portions thereof and of the work positioned thereon will be brought before the operator standing at a given station, a trough being conveniently provided at the lower side of the table so that liquids and other waste material scraped from the skins during putting-out operations thereon will be discharged from the table and conducted away by the trough. Preferably, and as indicated, the work support is provided with a surface layer frictional to a degree such that drying boards for skins may be supported upon the inclined table without sliding therefrom during the putting-out operations on the skins carried by said drying boards. Because of this frictional surface it is not necessary to provide cleats or other devices to hold the drying board

in place on the rotating work support. During the rotation of the table, which is preferably continuously in one direction, the operator slicks out the skin progressively as successive portions are brought before him on the rotating table and the tanning or dyeing liquids and other waste material are discharged into the trough at the lower side of the work support or table.

These and other features and characteristics of the invention will now be described in detail in the specification and then pointed out more particularly in the appended claims.

In the drawing, Fig. 1 is a perspective view of an apparatus illustrating one embodiment of the invention;

Fig. 2 is a vertical sectional view of Fig. 1; and Fig. 3 is a plan view showing a drying board with a skin slicked out thereon.

In the illustrated construction, which is particularly designed for use in putting-out hides or skins upon drying boards, there is provided a rotary table 4 fixedly secured to the upper end of a shaft 6 (Fig. 2) mounted in bearings 8 and 10 carried by a bracket member 12 secured to the under side of a floor 14 which forms the bottom of a box 16.

Upon inspection of Fig. 1 it will be observed that the box 16 is mounted upon posts or legs 18 and 20, the posts 20 being longer than the posts 18 so that the box 16 is inclined substantially, whereby liquids expressed from a piece of work on the table 4 will tend to collect at the lower front end of the box 16, a pipe 22 being provided with its upper end opening at one corner of the box to serve as a discharge pipe for any liquid draining to the lower side of the box 16.

In order that the upper work supporting surface of the table 4 may remain always in the same plane during rotation of the table, its supporting shaft 6 and the bearings 8 and 10 are supported at an angle to the vertical corresponding to the desired inclination of the upper surface of said table 4.

Upon inspection of Fig. 2, it will be observed that the bracket 12 is also provided with two horizontal bearings 24, 26 for a shaft 28 to the outer end of which is secured a pulley 30 about which passes a belt 32 (Fig. 1) which also passes around a pulley 34 on the armature shaft 36 of a motor 38. At the inner end of the shaft 28 there is a worm gear indicated in dotted lines at 39 arranged in mesh with a worm wheel 40 secured to the lower end of the shaft 6. In this way there is provided means for driving the shaft 6 and thus rotating the table 4 continuously in one direction at a rela-

tively low rate of speed predetermined by the ratio of the worm gear to the worm wheel 40.

Conveniently the motor 38 is electrically driven and is controlled from a switch (not shown) 5 mounted in a switch box 42 (Fig. 1) below the front end of the box 16, the switch being controlled through a link connection 44 to a treadle 46 pivotally mounted upon a bracket 48 below the front or lower end of the box 16 in a position readily accessible to the foot of the operator who stands at this lower end of the box 16.

While any suitable means may be provided for holding a drying board 52 (Fig. 3) against displacement while it is resting on the upper surface 15 of the table 4 during rotation of the latter, it has been found sufficient to provide said upper surface of the table 4 with a sheet of rubber 50 containing gritty material or otherwise provided with a friction surface so that the drying board does not readily slide thereon. This rubber sheet 50 also protects the upper surface of the table 4 from the watery material expressed from the skins and thus prevents warping of the table 20. It will be understood, of course, that other 25 means may be provided for preventing displacement of the drying board, such for instance as cleats, properly spaced with respect to the circumference of the table 4, should such be thought desirable.

In operating the apparatus, a drying board such as that shown at 52 in Fig. 3 is placed upon the table 4, after which a skin 54 is thrown upon the drying board in such manner as to be at least partially spread out, so that the operator 30 will have no trouble in using his slicker blade in spreading out the skin and in removing water therefrom. After a preliminary stroke or two of the slicker blade, the operator steps on the treadle 46 thus initiating rotation of the table 4. During rotation of the table the operator continues to slick out successive portions of the skin as they are presented to him during the rotation of the table. It has been found convenient, and conducive to rapid handling of the work, to have 35 another workman stand at either the right or left hand of the operator, depending on the direction of rotation of the table, to insert staples or tacks by which the skin is secured to the drying board, the tacks or staples being progressively inserted during the rotation of the table in those 40 portions of the skin which have just been slicked out by the operator handling the slicker blade. The workman who serves as tacker may remove the work from the table 4 at the end of the slicking-out and tacking operations while the operator is preparing to place another drying board on the table and to superpose a skin thereon preliminarily to another slicking-out and tacking operation.

Having described my invention, what I claim as new and desire to secure by Letters Patent of the United States is:

1. That improvement in treating skins fresh from tanning or dyeing solutions which comprises

moving marginal portions of a skin spread out on a drying board continuously past a given station, performing slicking-out operations on successive portions of the skin during continuous movement of the latter, and simultaneously with the slicking out of successive portions of the skin inserting fastenings in margins of the slicked-out portions to secure the skin to the drying board, the inserting of fastenings in the margins following promptly after the slicking out of each successive portion of the skin so that slicking out and fastening inserting operations are being performed substantially simultaneously upon successive portions of the skin.

2. In an apparatus for use in slicking-out operations upon skins and other similar pieces of work, a rotary work support mounted at a substantial angle to the horizontal, means under the control of the operator for rotating the work support, and a trough at the lower side of the work support positioned to receive liquids and other waste material removed from a skin on the rotary support during putting-out operations thereon.

3. In an apparatus for use in the treatment of skins, a shaft inclined from the vertical, a work support secured to the upper end of said shaft at a substantial angle to the horizontal, means under control of the operator to rotate the shaft and work support continuously in one direction 30 while a skin on the work support is being intermittently treated to remove liquid and other waste material therefrom, and a trough at the lower side of the work support positioned to receive such liquid and other waste material from 35 the skin and the work support.

4. In an apparatus for use in the slicking out of skins, a shaft arranged at a substantial angle to the vertical, a table secured to the upper end of the shaft at a substantial angle to the horizontal, said table having means to support a drying board having a skin thereon against sliding displacement, means under control of the operator to rotate the table, whereby successive portions of the skin are presented for slicking-out 40 operations by an operator standing at the lower side of the table, and a trough at said lower side of the table to receive the liquids and other waste material slicked out from the skins.

5. In an apparatus for use in the slicking out 50 of skins, a shaft arranged at a substantial angle to the vertical, a table secured to the upper end of the shaft at a substantial angle to the horizontal, said table having a surface of sufficient frictional quality to support a drying board having a skin thereon against sliding displacement, means under control of the operator to rotate the table, whereby successive portions of the skin are presented for slicking-out operations by an operator standing at the lower side of the table, 60 and a trough at said lower side of the table to receive the liquids and the other waste material slicked out from the skins.

MATTHEW M. MERRITT.
